Inventor
Edwin E. Joslin

By His Attorney
Thomas Bilyeu

UNITED STATES PATENT OFFICE.

EDWIN E. JOSLIN, OF PORTLAND, OREGON.

AUTOMATIC LIQUID CONTROL.

Application filed March 6, 1923. Serial No. 623,207.

To all whom it may concern:

Be it known that I, EDWIN E. JOSLIN, a citizen of the United States, residing at 469 Salmon Street, in the city of Portland, in 5 the county of Multnomah and the State of Oregon, have invented a new and useful Improvement in Automatic Liquid Controls, of which the following is a specification.

10 My invention is intended for use in apartment houses, residences, hotels, factories and all places where water is being drawn for personal or other uses and where it is necessary to maintain a supply on hand in 15 advance of the use of the same, this condition exists in so many places in modern life and so much trouble is had with existing devices that I set out some time ago to devise means that would accomplish the result and 20 at the same time lessen the troubles incident to the use of the present devices and at the same time to lessen the cost of installation of the same as a first cost.

For a more complete description of my 25 invention reference is made to the accompanying drawings in which—

Fig. 1 is a side elevation of a control box, into which the water is admitted from the source of supply and from where it is distributed to the various other points of use, it is assumed for the purpose of this description that the same is to be used in a structure wherein water is being distributed to various compartments on the same level, 30 on certain floors, and that the operating conditions will be the same, but it is assumed that I do not wish to be limited in the patent protection to be asked for and to be granted that I am to be limited to 35 the same in its application for use on water; as any liquid may be regulated and controlled by this device. The side of the container as shown in Fig. 1 is partially broken away to better illustrate the inner construction of the same and to show the method of journaling and controlling my siphon arrangement that I have utilized in the operating of the same. Fig. 2 is a side elevation of the control box, also, but illustrates the same from the opposite side from 40 that shown in Fig. 1 and shows the float controls and how the same regulate the level of the liquid to be controlled. Fig. 3 is a top plan view of the same, but shows the transverse partition that separates the container into two separate and distinct

compartments one for the retention of the liquid until the same should be required for use, and the other to be used as a container through which the liquid is to pass to the 60 place of ultimate use.

Fig. 4 is an inverted plan view of an adjustable control valve that may be placed in the bottom of a drip-cup mounted upon the float control of a master tank.

Referring to said views, wherein similar characters of reference indicate like parts throughout the same, the reference numeral 1 designates a master control tank of my invention, preferably of rectangular configuration and divided into receiving and discharge compartments 2 and 3, respectively, by the vertical partition 5. The receiving compartment 2 is of relatively large capacity and is supplied with water through 70 an inlet pipe 6 communicating with a source of water supply under pressure. Water is admitted from said inlet pipe and controlled by a valve 7 of any well known type as used in flush-tanks adapted to be opened and 75 closed in accordance with the level of water in the compartment 2 by the float 8.

A tubular yoke 10 is journaled for partial rotation in the side walls of said tank and in said partition. Said yoke extends at one 80 end through one of said side walls and is provided at the outside with a lever 11 through which it may be oscillated. In said compartment 2 said yoke is provided with a short branch pipe 12 having an upturned 85 goose-neck 13 at its opposite open end. Said open end desirably projects slightly above the water when in elevated position but owing to said goose-neck a water seal is maintained through which a siphonic effect 90 is obtained when the pipe end is lowered, as will be explained more in detail. In the crook of said goose-neck a hollow ball-float 15 is rigidly secured, as by clip 16. Secured 95 near the extremity of said goose-neck is a bracket 17 extending horizontally when the pipe 12 is raised in its uppermost position, as indicated in full lines in Fig. 2, and is provided with a circular boss 18 at its outer 100 end affording a socket for a vertically disposed cylindrical cup 20. Drip-openings 21 to drain said cup are provided in said socket, which openings may be adjusted to a predetermined extent of opening by means of a perforated plate 22 secured by a central 105 screw 23.

25 indicates a short branch-pipe commu-

natively connected to said yoke and disposed within the discharge compartment 3. Said pipe is similar to the pipe 12, being provided with a corresponding upturned 5 goose-neck 26, and constitutes the discharge leg of an inverted siphon which is operable when said goose-neck ends are depressed to draw water into the receiving end 12. 27 designates an outlet for the discharge of 10 water from the compartment 3.

The operation of the invention may be described as follows: With the control tank apparatus in its normal quiescent condition, as indicated in full lines in Figs. 1 to 3, inclusive, the receiving compartment 2 is full 15 of water to near the top of the partition while the compartment 3 is empty. Upon the operating of the lever 11 the yoke 10 is oscillated to lower said pipes 12 and 25 and 20 submerge the open end of the former whereby a siphonic effect is produced causing the water to flow from the compartment 2 to the compartment 3 through the pipe 12, the tubular yoke 10, and the pipe 25. The ball- 25 float 15 is submerged with said goose-neck 13 and has a tendency to lift the pipe 12 to the top of the water but such action is resisted by the gravity of the water contained in the cup 20 which is filled with water as 30 the pipe 12 is lowered, as indicated in broken lines in Fig. 2, and as the water contained in compartment 2 recedes tends to depress said pipe in opposition to the buoyancy of the float until the regulated leakage 35 from said cup through apertures 21 allows the float to raise the goose-neck 13 above the level of the water and to its original position.

Water flowing from the receiving compartment passes through pipe 25 into the discharge compartment and thence through the discharge outlet 27.

Having described my invention, what I claim, is:—

45 1. Automatic liquid control apparatus, consisting in a tank including a receiving and a discharge compartment, said receiving compartment having communication with a source of water supply under pressure, a float-controlled valve admitting water from said source when the water-level is lowered, a tubular yoke journaled to oscillate in said tank, said yoke having an exteriorly disposed tripping lever, tubular 50 legs communicatively connected with said yoke and extending into said compartments, respectively, said legs and yoke forming an inverted siphon to convey water from said receiving compartment to the discharge compartment, said legs having an upturned 55 goose-neck at their outer ends, a float connected to the outer end of the intake leg positioned in the receiving compartment, a cup rigidly secured to the outer extremity of said intake leg, said cup having an adjustable leak-aperture in its bottom, and means to trip said lever at a distance 60 from said tank.

forated bottom, and a similarly perforated plate pivotally secured to said bottom whereby the leakage through said perforated bottom may be regulated.

2. Automatic liquid control apparatus, 70 consisting in a tank including receiving and discharge compartments, said receiving compartment having communication with a source of water supply under pressure, a float-controlled valve admitting water from 75 said source when the water-level is lowered in the tank, a tubular yoke journaled to oscillate in said tank, said yoke having an exteriorly disposed tripping lever, tubular legs communicatively connected with said 80 yoke and extending into said compartments, respectively, said legs and yoke forming an inverted siphon to convey water from said receiving compartment to the discharge compartment, said legs having an upturned 85 goose-neck at their outer ends, a float connected to the outer end of the intake leg and positioned in the receiving compartment, and a cup rigidly secured to the outer extremity of said intake leg, said cup having 90 an adjustable leak-aperture in its bottom.

3. Automatic liquid control apparatus, 95 consisting in a tank including receiving and discharge compartments, said receiving compartment having communication with a source of water supply under pressure, a float-controlled valve admitting water from 100 said source when the water-level is lowered in the tank, a tubular yoke journaled to oscillate in said tank, said yoke having an exteriorly disposed tripping lever, tubular legs communicatively connected with said yoke and extending into said compartments, respectively, said legs and yoke forming an inverted siphon to convey water from 105 said receiving compartment to the discharge compartment, said legs having an upturned goose-neck at their outer ends, a float connected to the outer end of the intake leg and positioned in the receiving compartment, a cup rigidly secured to the outer extremity of said intake leg, said cup having 110 an adjustable leak-aperture in its bottom, and means to trip said lever at a distance 115 from said tank.

4. In automatic liquid control apparatus, a tank having a water receiving compartment and a water discharge compartment, float-controlled means of water supply for 120 said receiving compartment, and a float-controlled oscillating siphon arranged to convey water from said receiving compartment to the discharge compartment.

5. In automatic liquid control apparatus, 125 a tank having a water receiving compartment and a water discharge compartment, float-controlled means of water supply for said receiving compartment, an oscillating siphon arranged to convey water from said receiving compartment to the discharge 130

compartment, a float secured to said siphon within the receiving compartment to elevate the end of said siphon above the liquid, and means to retard the floatative action of said float upon the siphon.

6. In automatic liquid control apparatus, a tank having a water receiving compartment and a water discharge compartment, float-controlled means of water supply for said receiving compartment, an oscillating siphon arranged to convey water from said receiving compartment to the discharge compartment, the legs of said siphon terminating in upwardly directed goose-necks, a float secured to one of said siphon legs within the receiving compartment to elevate the end of said leg above the liquid, and means to retard the lifting action of said float upon the siphon.

7. In automatic liquid control apparatus, a tank having a water receiving compart-

ment and a discharge compartment, float controlled means to supply water to said receiving compartment, an oscillating siphon having a leg with upwardly curved 25 open end in each said compartment, a float secured to said end of the intake leg of said siphon tending to maintain the intake opening above the water level, and a cup secured to said intake leg having a leak therein 30 arranged to be filled with water as said leg is lowered to retard the lifting of said intake leg.

8. In automatic liquid control apparatus, a tank divided into two compartments, a 35 tiltable siphon having a leg in each said compartment, a float secured to the extremity of one said leg, and a cup secured to the extremity of said leg provided with adjustable leak-holes therein.

EDWIN E. JOSLIN.
